UNITED STATES PATENT OFFICE.

GEORGE MESSIG, OF BROOKLYN, NEW YORK.

TIMER AND DISTRIBUTOR.

Application filed March 20, 1922, Serial No. 545,329. Renewed January 26, 1926.

This invention relates to improvements for igniting the charge in internal combustion engines and it is more particularly adapted for use in those engines in which 5 the method of high tension ignition is applied.

The primary object of the invention is to provide a compact device whereby one induction coil may be used with a source of 10 current and the increased voltage distributed and timed to cause the ignition of the compressed gases in any number of the co-acting cylinders with less wiring, fewer parts and more economy of space than ordinarily employed.

Another object of the invention is to provide a distributor wherein the central stem or trunk conductor is connected by suitable devices at proper intervals to terminals disposed 20 on the inner face of a cylindrical casing or shell, which terminals are in turn connected to cables at the end of the casing for distributing the current to suitable translating devices or spark plugs.

25 A further object of the invention is to provide an efficient means for varying the time occurrence of the sparks relatively to the cycle of operations so that the spark may be advanced or retarded as the varying speed of the engine or other conditions 30 may require.

Another object of the invention is to provide a timer having a revoluble contact member and a plurality of contacts in the shell of the timer, and means to periodically close the same primary circuit between each contact and a vibratory coil, and another series of contacts in the shell of the time, the said coil being also in circuit with 35 a device carried by the contact maker rotating in the shell to successively distribute the high tension current to the last named contacts and thence to corresponding spark plugs.

45 A still further object of the invention is to provide a mechanism which may be easily and quickly dismounted and remounted for purposes of examination, replacement or repair, and to include in a small compass a timer and distributor for the ignition current comprising a distributor part for conveying the secondary ignition or spark current of the coil to the leads of the various 50 spark plugs of internal combustion engines.

55 With the above named objects of the invention and other objects and purposes,

which will be described below, in view, the invention consists in the construction, arrangement, combination and operation of parts hereinafter set forth, the whole forming 60 a comparatively simple organization which is reliable and efficient in practical use.

In the drawings, illustrative of one embodiment of the invention, which accompany 65 and form a part of this specification,—

Figure 1 represents a diagrammatic view of the improved system in general;

Figure 2 is a diagrammatic view of the working parts of the mechanism employed 70 by me together with circuits therefor;

Figure 3 is a view in section of my casing and interior parts;

Figure 4 is a plan bottom view of the shell; 75

Figure 5 is a side elevation of the same;

Figure 6 is a plan view of the cover;

Figure 7 is a side elevation thereof;

Figure 8 is a plan view of my rotatable disk; 80

Figure 9 is a side elevation of the latter and of the cover; and

Figure 10 is a partial plan view of another distributor member made according to my invention. 85

Referring particularly to the drawings, the reference numeral 1 denotes a motor equipped with my ignition device and indicates in the present instance a four cylinder internal combustion engine carrying 90 spark plugs 2, 3, 4 and 5 respectively connected with terminals 23 in my timer and distributor by cables 2', 3', 4' and 5'.

A revoluble primary contact member 16 is enclosed within my timer and distributor 95 and is rotated by a rotary shaft 6 which may be suitably connected with the engine shaft, as for example by gears 7. My vibratory coil is designated at 8 and may be connected with a wire 9' of a source of power as the 100 battery 9, or with a wire 26 of a magneto. In cases where a battery is used it may be grounded by a wire 10. The coil is also put in electrical connection with my timer by the wire 11 of the primary circuit of the coil and the wire 12 of the secondary circuit, in which circuits the primary and secondary contacts are located as herein-after set forth. My timer and distributor comprises an insulating shell or body portion 105 of the casing 18 having a cover 14 suitably held in position as by screws 14'

and a leaf spring 20. A rotatable insulating disk 15 is carried around by the member 16 being positioned above an annular ledge or rim 18 of the casing, the shaft 6, sleeve contact member 16 and rotatable disk 15 all being concentric. The said disk 15 serves to divide the casing 13 into two compartments, in the lower one of which are located the primary circuit interrupting devices and in the upper portion thereof are contained the secondary circuit switching distributing means.

By the revolution of the said sleeve 16, which is preferably keyed to the shaft 6, the primary circuit is alternately interrupted and completed by the contact member or actuator 16' which is spring controlled and located at the end of the member 16 and makes electric connection serially with the contacts formed by the open end leaf bowed springs 17 which are arranged to provide a series of spaced contact points all of which are connected by the conducting ring 24 and are located in the primary circuit of the coil 8 by the wire 11 running from one of the stationary primary contacts on binding posts 11' of said springs to the said coil.

On the under side of the cover 14 a conducting ring 19 is located which ring is interposed in the secondary circuit of the coil 8 by means of the wire 12 running from the secondary terminal or binding post 12' near its periphery of the cover to the said coil. A conducting spring finger 21 carried by a section 15' of the rotatable disk 15 bears continuously against the ring 19 and a preferably spring controlled movable secondary distributor or arcuate member 22 attached to said finger consecutively contacts during every revolution thereof the adjustable secondary distributing contacts 23 which are respectively placed in circuit with the spark plugs 2, 3, 4 and 5 by the connecting cables 2', 3', 4' and 5'.

The shell 13 may have a suitable support, as at 25, and be held to the same by the spring 20 and adjusted for timing purposes by the manipulation of the lug 25' carried by the said shell. The high tension contacts in the casing 13 may be adjusted so as to lie flush with the interior face of the shell as at 23' in Figure 10 and contact therewith may be made by a roller 22' supported by resilient means 30 carried by the section 15' of the rotatable disk 15, thus providing a spring support for the roller on each side of the same.

It will thus be noted that I have devised means wherein in apparatus of the class described one of each of a plurality of contacts consecutively closes or interrupts the same primary circuit of a single vibratory coil by a suitable contact member, which coil is also in circuit with a device carried

by the revolute contact member, the said device being constructed and arranged to distribute at the proper time the high tension current from the said coil to various spaced contacts arranged in the path of the contact member and therefore to each corresponding cylinder of the internal combustion engine.

I wish it to be understood that I do not desire to be limited to the particular use or the exact details of construction shown and described, for obvious modifications will occur to persons skilled in the art.

What I claim as my invention is:

1. In a device of the class described, a casing carrying distributor terminals and a fixed terminal attached to a conducting ring having resilient fingers, a cover therefor having a high tension terminal and a conducting ring connected therewith, an intermediate rotatable block with a resilient conducting brush in electrical contact with the high tension conducting ring and adapted to successively engage the distributor terminals, and a spring contact adapted for simultaneous rotation with said block and located in the path of said resilient fingers.

2. In a device of the class described, a casing carrying distributor terminals and a fixed terminal attached to a conducting ring having resilient fingers adapted to be individually detached from the ring at will, a cover therefor having a high tension terminal and a conducting ring connected therewith, an intermediate rotatable block with a resilient conducting brush in electrical contact with the high tension conducting ring and adapted to successively engage the distributor terminals, and a spring contact adapted for simultaneous rotation with said block and located in the path of said resilient fingers.

3. In a device of the class described, a casing carrying distributor terminals and a fixed terminal attached to a conducting ring having resilient fingers, a cover therefor having a high tension terminal and a conducting ring connected therewith, an intermediate rotatable block with a resilient conducting brush in electrical contact with the high tension conducting ring and adapted to successively engage the distributor terminals, and a spring contact adapted for simultaneous rotation with said block and located in the path of said resilient fingers, and also resilient means to hold its conducting ring in operative position and the cover to the casing.

4. In a device of the class described, a casing carrying distributor terminals and a fixed terminal attached to a conducting ring having resilient fingers, a cover therefor having a high tension terminal and a conducting ring connected therewith, an intermediate rotatable block with a resilient con-

- ducting brush in electrical contact with the high tension conducting ring and having an arcuate member adapted to successively engage the distributor terminals, and a spring contact adapted for simultaneous rotation with said block and located in the path of said resilient fingers. 20
5. In a device of the class described, a casing carrying adjustable distributor terminals and a fixed terminal attached to a conducting ring having resilient fingers, a cover therefor having a high tension terminal and a conducting ring connected therewith, an intermediate rotatable block with 10
- 15 a resilient conducting brush in electrical contact with the high tension conducting ring and adapted to successively engage the distributor terminals and a spring contact adapted for simultaneous rotation with said
- block and located in the path of said resilient fingers. 25
6. In a device of the class described, a casing provided with distributor points, a terminal attached to a conducting ring provided with resilient fingers, a cover therefor having a high tension terminal and a conducting ring embedded therein, a rotatable block with a conducting brush in contact with said last mentioned ring and adapted to successively engage the distributor points 30 and a contact adapted for simultaneous rotation with said block and located in the path of said resilient fingers. 35

Signed at Brooklyn in the county of Kings and State of New York this 12th day of November A. D. 1921.

GEORGE MESSIG.
